THREAD WINDING APPARATUS

Francis B. Breazeale, Hendersonville, N. C., assignor to American Enka Corporation, Enka, N. C., a corporation of Delaware

Application January 18, 1951, Serial No. 206,693

10 Claims. (Cl. 242—45)

1 This invention relates to the winding of threads, and more particularly to a method and apparatus for the winding of a thread at substantially constant tension onto a take-up device that produces a cyclically varying thread velocity from the thread supply to the take-up device.

In the textile art, a thread is often collected upon a take-up means of non-uniform radius at a point thereon which is subject to a regularly re-occurring variation in position, which in turn produces a regularly varying thread velocity. When the thread is then drawn through a tensioning device, a corresponding variation in thread tension is obtained which may be extremely undesirable.

Considering the most simple case with which this invention is concerned, a thread may be wound through a guide onto a rectangular flat card or board, the thickness of which is negligible in comparison with its width. This card or board is rotated about the axis mid-way between its parallel edges at constant R. P. M. During this rotation, the point of collection is the edge of the card or board, which therefore follows a circular path. Obviously, the velocity of the thread through the guide is not uniform. This situation is encountered in applications such as the winding of thread onto a small card for gloss examinations or onto a large seriplane board for evaluation of properties such as fiber quality, 30 milkiness, and the like.

In such applications the thread is customarily passed from a source of supply through a tensioning device, over a traversing device, and then onto the collection device. The tensioning device should impart a low but fixed tension to the thread as it is being wound. This uniform tension is necessary in order to permit a reliable comparison of the threads at the outer edges of the card or board with the threads at the inner portions. For example, it has been found in the winding of seriplane boards with rayon threads of fine denier, that if the tension is too high, these threads will be harmed to such an extent that milkiness may be found in the threads. Since 45 this milkiness is not characteristic of the threads themselves, it prevents a reliable evaluation of the inherent milkiness therein.

This applies to the winding of fine denier rayon threads onto gloss cards. Since the light reflecting ability is determined from these threads as wound on the card, it is essential that the winding tension be extremely uniform.

It is therefore an object of this invention to compensate for the variation in the thread ve-

locity caused by winding a thread from a source through a tensioning device onto a collection means of non-uniform radius rotating at constant angular velocity, so that a constant thread velocity through the tensioning device and a substantially constant winding tension are thereby obtained.

It is contemplated, according to this invention, to provide a thread-storage device interposed between the tension device and the collection means, the amount of thread stored thereon being variable, positively controlled, and synchronized with the angular position of the rotating non-uniform collection means in such a manner that the thread velocity through the tensioning device is constant.

It is a further object of this invention to wind a thread upon a rotating collection means of non-uniform radius at a substantially constant tension.

It is a still further object of this invention to synchronize the angular position of a rotating collection means of non-uniform radius, onto which thread is being wound, with the amount of thread retained in a thread storage device so that the thread enters the storage device at a constant velocity.

An additional object is to provide an apparatus for the winding of thread onto a rotating collection means of non-uniform radius at a substantially constant tension.

Other objects and advantages of this invention will be apparent from the following detailed description of an embodiment thereof utilized for winding gloss cards when considered in conjunction with the accompanying drawings wherein:

Figure 1 is a schematic view of winding apparatus embodying the tension compensating and stabilizing device of the present invention;

Figure 2 is a detail view in side elevation of the cam follower and movable thread roller assembly of the tension compensating and stabilizing device;

Figure 3 is a side view of the clamp used to support the gloss card onto which threads are being wound;

Figure 4 is a plan view of the clamp of Figure 3;

Figure 5 is a schematic drawing of a gear train taken immediately behind the frame of the apparatus as shown in Figure 1;

Figure 6 is a perspective view of a flat rectangular card rotating about the axis A—A, which is parallel to both long edges of the card and midway between them;

Figure 7 is a perspective view of a flat rectangular card rotating about the axis A—A, which is not midway between the edges of the card;

Figure 8 is a perspective view of a prism rotating about the axis A—A, which is the central axis of the prism; and

Figure 9 is a perspective view of a prism rotating about the axis A—A which is not the central axis of the prism.

Referring now in greater detail to Figure 1, a thread designated by the numeral 10 is shown entering the apparatus from a source of supply, not shown, through a thread guide 11 attached to a frame generally indicated by the numeral 12. From guide 11 the thread passes through a drag imparting tensioning device 13, over fixed roller 14, under movable roller 15, over fixed rollers 16 and 17, and through traversing guide 18 to collection on gloss card 19.

Tensioning guide 13 may be any of the various types well known in the art. The disc type shown in Figure 1, on which annular weights can be added to press the two discs together with whatever force may be desired, has been found to be satisfactory. Fixed rollers 14, 16 and 17 are frictionless, freely rotatable, thread-driven rollers which are also well known in the art. Roller 15 is similar to fixed rollers 14, 16 and 17 except that it is mounted to reciprocate vertically in a manner to be more fully described hereinbelow.

Referring now to both of Figures 1 and 2, it can be seen that the roller 15 is mounted upon a stud extending horizontally from a rod 20 which is mounted for vertical sliding movement in a sleeve 21, which in turn is mounted from frame 12 by means of bracket 22. On the lower end of rod 20 a cam follower 23 is mounted for coaction with a cam 24, the design of which will be described. Around rod 20 there is provided helical spring 25 having its upper end bearing against the lower shoulder of sleeve 21 and its lower end bearing against a collar 26 affixed to rod 20. The spring 25 acts in compression and thus urges rod 20 and cam follower 23 downwardly. A stop collar 27 is affixed to rod 20 above sleeve 21 to limit the extent to which spring 25 can force rod 20 in a downward direction. The cam 24 is fastened to a cam shaft 28, which is rotated at a constant R. P. M. by driving means, best shown in Figure 5.

Fixed rollers 14 and 16 are separated a small distance equal to the diameter of movable roller 15, and are supported from the frame 12 to lie in the same vertical plane as the roller 15. In this manner the thread passes from roller 14 vertically downward and around 15 and vertically upward to roller 16 so that the two parts of the loop thus formed are parallel.

Traversing guide 18 is slowly reciprocated as gloss card 19 is rotated to lay the thread upon the card in closely spaced parallel convolutions. This traversing may be effected by any of the systems known in the art, such as the mechanism schematically shown in Figure 1 which comprises the traversing guide 18 that is affixed to reciprocating guide bar 29, cylindrical traversing cam 30, and a pin cam follower 31 affixed to guide bar 29 and riding in the helical cam grooves in cam 30 in the well known manner. Cam 30 is rotated by any suitable means, not shown. The traversing system per se does not constitute a part of this invention except in the manner that it is combined with the other elements of the apparatus of this invention.

Gloss card 19 can be of any suitable material,

as for example, heavy black cardboard. The card is clamped between a fixed support 32 fastened to flange 33, and a movable support 34, which is provided with two holes through which tightening bolts 35 and 36 are free to pass, see Figures 3 and 4. In fixed support 32 two threaded holes are provided for engaging bolts 35 and 36. Shoulders on these two bolts serve to force support 34 against support 32 as the two bolts are screwed in. Obviously, other similar clamps may be used to equal advantage in this application. Circular flange 33 is rigidly affixed to one end of winding shaft 37, which in turn is driven at a constant R. P. M. by suitable driving means shown in Figure 5.

Using the embodiment shown in Figure 1, it is necessary that the R. P. M.'s of cam shaft 28 and winding shaft 37 be identical. It is also necessary that means be provided for synchronizing cam shaft 28 and winding shaft 37 so that their angular relationships may be maintained constant.

One gear train that can be used to accomplish the synchronization of shafts 28 and 37 is shown in Figure 5, which is a schematic drawing of the parts just behind frame 12. In this figure, cam shaft 28 and winding shaft 37 are seen in the same relation that they are seen in Figure 1. Frame 12 may be provided with any suitable base, designated 38, on which is fastened electric motor 39. Attached to the driving shaft of motor 39 is a small spur gear 40 which meshes with gear 41. Gear 41 is keyed to cam shaft 28, to which gear 42 is likewise keyed. Idler gear 43 meshes with gear 42 and transmits its rotation to gear 44, which is keyed to winding shaft 37. It can thus be seen that rotation of the electric motor is transmitted to cam shaft 28 at a lower R. P. M. Next, this R. P. M. of cam shaft 28 is transmitted to winding shaft 37, which rotates in the same direction and at the same R. P. M. as cam shaft 28.

The shape of cam 24 is determined from consideration of the angular position and dimensions of gloss card 19 and the distance between gloss card 19 and traversing guide 18. The development of the surface of this cam 24 is such that at any given time the linear velocity of the thread passing through tensioning device 13 is constant, which will be more readily understood from the following discussion.

As gloss card 19 is rotated at a constant R. P. M., the effective point of thread take-up is the edge of card over which the free end of the thread is passed. With the card rotating at a fixed R. P. M. and with the dimensions of the card known, it thus can be seen that the average linear take-up velocity of the thread can be immediately determined. For example, with a 3-inch card rotating at 180 R. P. M. the average linear take-up velocity is 30 yards per minute. It is obvious that the thread is not always collected at this average velocity, for although the point of collection moves at a constant peripheral speed, the distance of this point from the point of supply, in this case traversing guide 18, does not increase at a fixed rate.

Designating as α the angle formed by the card with the line connecting the axis of rotation of the card and the traversing guide, it can be realized that during the earliest part of the cycle, when α is small, the point of collection is moving in a direction substantially perpendicular to this line. In this case, the distance between the guide and point of collection increases relatively slowly. As α increases, the point of collection

tion reaches a certain position at which the rate of distance increase is a maximum. The value of α at which this is obtained, designated α_m , depends on the size of the card and its distance from the traversing guide, and is the value of α at which the line between the traverse guide and the edge of the card is tangent to the circular locus of the edge of the card. After α reaches α_m and increases toward 180° , the rate of distance increase falls off gradually until at 180° it is zero. At this point the opposite edge of the card starts collecting thread and a new cycle commences.

The rate of distance change, or velocity, of the thread thus varies periodically every 180° , and to prevent a corresponding tension variation, this velocity variation through the tensioning device must be eliminated. Accordingly, through the co-action of cam 24 and cam follower 23, movable roller 15 is reciprocated in such a manner that the amount of yarn stored in the loop between rollers 14, 15 and 16 balances the varying rate of thread withdrawal by card 19. That is, the thread storage system is designed to accumulate thread from the thread supply whenever the card take-up velocities are lower than the average velocity, and to furnish thread to the card in excess of the thread furnished from the thread supply whenever the card take-up velocities are higher than the average velocity.

In operation this device is extremely simple. The thread passes through guide 11 and tensioning device 13 to the thread storage system comprising rollers 14, 15 and 16, after which it passes through traversing guide 18 onto gloss card 19. As viewed in Figure 1, winding shaft 31 and cam shaft 28 both rotate counterclockwise in synchronism at the same R. P. M. while roller 15 reciprocates in such a manner that the varying velocities of the thread passing over rollers 16 and 17 and through guide 18 are compensated by the varying length of the thread in the loop between rollers 14, 15 and 16.

In practice, the inertia of rollers 16 and 17 to the changes in velocity of thread passing thereto may prevent the tension of the thread being wound from being perfectly constant. These general variations, however, are so minor that for the purposes involved the tension is substantially constant.

The embodiment described above represents the invention in perhaps its most elementary form. Both the winding shaft and the cam shaft turn in identical angular velocities. It would be possible, of course, to so design the cam that it would be a four-cycle cam, for example, instead of the two-cycle type, as shown. In this case the cam shaft would rotate at one-half the angular velocity of the winding shaft.

The same principle as described above would be applied to the design of an apparatus for use with a seriplane board winding system.

Also contemplated by this invention is the winding of a thread onto a rotating collection means of non-uniform radius other than the flat card or board described above. The embodiment described above, a flat rectangular card rotating about an axis midway between its long edges, is shown in Figure 6, but it could be modified so that rotation would be carried out about an axis not midway between its parallel edges, as shown in Figure 7. Also, a prism could be attached to the winding shaft and rotated about its central axis as shown in Figure 8, or it could be rotated about a non-central axis as shown in Figure 9.

It is preferable to rotate the collection device, whether a card-shaped member, triangular member, or other, about a central axis, or axis of symmetry, if there be one. It is possible, however, to rotate the collection device about a non-central axis, for the cam surface can be developed in a similar fashion to give a constant velocity of thread through the tensioning device.

Other types of thread storage systems may be used in this apparatus, although from a practical standpoint the one described in the foregoing embodiment is perhaps the most simple. Any storage system could be used, however, which is capable of retaining a variable length of thread, the length retained being positively controllable.

It is therefore to be understood that this invention is not limited by the description of the embodiment given above.

What is claimed is:

1. An apparatus for winding a thread at substantially constant tension that comprises a rotatable collection device of non-uniform radius that imparts a cyclically irregular velocity to the thread passing thereto, a tensioning device in the thread path to the collection device, relatively movable guide means interposed in the thread path between said tensioning device and said collection device for storing therebetween a variable length of thread, and means unaffected by the tension of said thread for relatively moving said guide means to vary the length of thread stored by said guide means in synchronism with changes in the angular position of said collection device.
2. The apparatus defined in claim 1 wherein the collection device is a flat rectangular member.
3. The apparatus defined in claim 2 wherein said flat rectangular member rotates about its central axis.
4. The apparatus defined in claim 2 wherein said flat rectangular member rotates about an eccentric axis.
45. The apparatus defined in claim 1 wherein the collection device is a prism.
6. The apparatus defined in claim 5, wherein said prism rotates about its central axis.
7. The apparatus defined in claim 5 wherein said prism rotates about an eccentric axis.
8. An apparatus for winding a thread at substantially constant tension that comprises a rotatable collection device of non-uniform radius that imparts a cyclically irregular velocity to the thread passing thereto, a tensioning device in the thread path to the collection device, a pair of fixed freely rotatable thread-driven rollers and a movable like roller, said rollers being located in the thread path between said tensioning device and said collection device, means mounting said movable roller to reciprocate relative to said fixed rollers to form therewith a storage device of varying capacity, and means unaffected by the tension of said thread for reciprocating said movable roller in synchronism with changes in the angular position of said collection device, whereby the velocity of the thread passing through said tensioning device is maintained constant.
9. An apparatus as defined in claim 8, wherein the direction of reciprocation of said movable roller is perpendicular to a line connecting the centers of said pair of fixed rollers.
10. An apparatus for winding a thread at substantially constant tension that comprises a ro-

7
tating collection device of non-uniform radius that imparts a cyclically irregular velocity to the thread passing thereto, a tensioning device in the thread path to the collection device, a pair of fixed freely rotatable thread-driven rollers and 5 a movable like roller, said rollers being located in the thread path between said tensioning device and said collection device, said rollers lying in the same plane, means mounting said movable roller to reciprocate relative to said fixed rollers in said plane to vary the sum of the distances from said movable roller to each of said pair of rollers, a cam follower attached to said movable roller, a cam coacting with said cam follower to reciprocate said movable roller, and 15 means to rotate said cam in synchronization with changes in the angular position of said collection

device, the surface of said cam being correlated with the dimensions of said collection device so that the thread velocity through said tensioning device is maintained constant.

FRANCIS B. BREAZEALE.
